(57) **CLAIM**

The ornamental design for a portion of forceps for medical robot, as shown and described.

DESCRIPTION

FIG. 1 is a front, top and right side perspective view of a portion of forceps for medical robot, showing our new design;

FIG. 2 is a front elevational view thereof; a rear elevational view being a mirror image thereof;

FIG. 3 is a top plan view thereof;

FIG. 4 is a bottom plan view thereof;

FIG. 5 is a left side elevational view thereof; and,

FIG. 6 is a right side elevational view thereof.

The broken line portion is for illustrative purposes only and forms no part of the claimed design.
